UNITED STATES PATENT OFFICE.

WILLIAM E. WINE, OF TOLEDO, OHIO.

RAILWAY CAR.

Application filed June 13, 1923. Serial No. 645,145.

My invention relates to the construction of railway cars and especially to those in which hinged doors are employed for closing hoppers through which the lading of 5 the car is discharged.

A primary object of the invention is to embody improved features of construction in the car doors and in portions of the car body adjacent thereto.

10 Another principal object of the invention is to provide improved means for forcing car doors to fully closed position from a position of partial closure.

The principal feature of the invention, 15 generally stated, consists in extending the sides of a railway car downwardly below the hinged doors closing the discharge openings in the car, portions of the sides adjacent the free edges of the doors being cut away so 20 that said sides at such points extend only slightly below the planes of the doors, and the doors being provided with supporting arms respectively extending outwardly beyond the plane of the neighboring portion 25 of the car side adjacent the free edge of the door. A further feature of the invention consists in providing a hinged door with a door supporting arm having formed therein a plurality of apertures either of which 30 is adapted to receive a removable door prying lever. Other features of the invention residing in particular constructions and in 35 advantageous combinations of parts will hereinafter appear and be particularly pointed out in the claims.

In the drawings illustrating a preferred form of the invention:

Figure 1 is a side elevation of a portion of a railway car embodying the invention.

40 Figure 2 is a sectional view on the line 2-2 of Figure 1, showing also in dotted lines certain clearance outlines A and B which control the dimensions of cars on many railroads and beyond which it is not 45 permissible for the car to extend.

In the construction illustrated in the 50 drawings 1 indicates the main portion of the car side. Along the lower edge of the side plate 1 and on the inner face thereof is secured a bottom flange angle 2 whose 55 projecting leg 3 extends inwardly toward the center of the car. Secured to the inner face of the car side 1 somewhat above the flange angle 2 is a side sheet extension 4. The plate 4 is bent inwardly to pass over the 55 inner edge of the projecting leg 3 of the flange angle and extends downwardly from said leg in a plane which is preferably substantially parallel to the general plane of the side 1 but somewhat nearer the longitudinal axis of the car than is the portion of the car side which is above it. Car stakes 60 or vertical stiffeners 5 may be secured to the outer face of the car side, the lower ends of said stakes preferably being disposed in 65 overlapping relation to the vertical leg of the flange angle 2. The lower edge of the side plate extension 4 is preferably provided with an outstanding marginal flange 6 serving to stiffen the lowermost portion of this 70 part of the car, both vertically and laterally.

The car illustrated is of the hopper bottom type provided with a plurality of hoppers. The structural details of only one of these hoppers at one side of the center line 75 of the car is illustrated in the drawings, but it is to be understood that the construction of the several hoppers is identical on both sides of the car. These hoppers are formed with transversely extending trough-shaped hopper plates 7 having end flanges 8 lying against the inner face of the plate 4 and secured thereto by means of rivets 9. Brace plates 10 of angular form may extend 80 across the lower edges of the hopper plate 85 7 for the purpose of stiffening the latter.

To close the hopper discharge openings between the longitudinally spaced lower edges 11 of adjacent hopper plates 7, two 90 hinged doors 12 are preferably employed for each opening, the doors being arranged in pairs and being hinged along their remote edges, at 13, to the lower edges of the hopper plate 7 and to the flanged brace plates 10 by means of suitable body and door 95 hinge members 14 and 15, respectively. The doors 12 may advantageously be constructed of steel plates having downwardly extending marginal stiffening flanges. The marginal flanges 16 at the sides of the doors 100 are reduced in height or cut away somewhat adjacent the free edges of the doors to enable the arms by which the doors are supported to project outwardly beyond the adjacent portion of the car side without requiring said arms to be unduly offset or 105 spaced from the plane of the door 12. The doors of each pair are preferably inclined

so that their adjacent free edges are at a slightly lower elevation than their hinged edges, the hinge pintles 13, which extend transversely of the car, being higher above the rails than are the free edges of the doors. When both doors of a pair are closed their free edges stand closely adjacent each other and, if desired, may be arranged to come into actual contact. The free edges of the closed doors are disposed slightly above the line of the bottom edge or lower marginal flange 6 of the side sheet extension 4.

The doors 12 may extend entirely across the car beneath the ordinary center sill construction, or the hoppers may be arranged to provide an opening for the center sills. Both of these forms of construction are well known in the art and the invention is equally applicable to either. In either form of construction it is customary to employ a stiffening beam, such as 17, which is secured to the door near the free edge thereof. In the illustrated embodiment of my invention the beam 17 is of bulb angle form, its short leg 25 engaging the undersurface of the door and its long leg outstanding therefrom. The stiffening member 17 is preferably disposed so that one of its legs projects outwardly from the underside of the door in spaced relation to the free edge of the latter, while its other leg, which engages and is secured to the door, extends away from the door hinge toward the free edge of the door. The bulb angle 17 may be of heavy section 35 and preferably is of less length than the full width of the car. Secured to the outer ends of the member 17 are door arms 18 which project outwardly beyond the plane of the side plate extension 4. These door arms 40 are preferably of somewhat less weight per foot than the bulb angle stiffeners 17 and may conveniently be in the form of angle irons. One leg of each of the angle irons 18 lies against and is secured to the back of the corresponding bulb angle 17, while the other leg of the angle engages the under surface of the adjacent door plate 12 and is rigidly secured thereto. Toward their outer ends the door arms 18 are bent or angled 45 downwardly away from the door so as to project outwardly beneath the lower edge of the neighboring portion of the car side extension plate 4. The outermost ends of the flanged door arms 18 preferably extend in a general horizontal direction so that the upper flanges 19 of said arms are disposed parallel to the planes of the doors to which they are respectively connected. The flanges 50 19 of the extension angle irons or door arms 18 form ledges or seats adapted to be engaged by door supporting hooks 20 pivotally mounted upon the side of the car. These hooks, the construction of which is now well known in the art and therefore 55 need not be described in detail, are pivoted

to the car side plate 4 by rivets 21 passing through suitable pivot brackets 22 which themselves are rigidly riveted to the said extension plate. If desired, rotatable locking cams 23 may be provided for maintaining 70 the hooks 20 in locked position.

In order that the door arms 18 may be positioned for advantageously cooperating with the hooks 20, the lower portions of the side plate extensions 4 are notched or cut 75 away, as at 24, so that the lower edges of said plates 4 in the neighborhood of the center of the hopper, substantially follow and are parallel with the planes of the cooperating doors when the latter are in closed position, the lower edges of the side plates being preferably slightly below the planes of the doors. By this means the angle iron door arms 18 may be extended outwardly 80 beyond the side plates 4 without greatly offsetting them and hooks of comparatively short length may be employed. Moreover, the notches 24 of the side plate extensions 4 result in eliminating the stiffening flanges 6 of said plates in the vicinity of the door 85 supporting hooks, thus permitting the latter to swing in a plane closely adjacent the plate 4 and thereby reducing the bending strains upon the door arms 18. To compensate for the removal of the marginal flange 6 in the 90 vicinity of the hooks, a flanged stiffening member 25, preferably formed from angle iron, is rigidly secured to the inner face of each side plate extension 4 by means of rivets 26. The angle iron 25 is bent so as 95 to provide inclined portions corresponding to the planes of the adjacent doors. The projecting leg of the angle iron 25 extends inwardly toward the center of the car and preferably constitutes a seat or shoulder beneath which the outer edges of the doors 100 12 stand when in closed position.

With doors of the character herein disclosed it is preferable that means be provided for sustaining them in partly closed 110 position as well as in fully closed position, and that means be provided for forcing them to fully closed position from their partially closed position. In the present instance, the supporting hooks 20 are respectively provided with supporting ledges 27 for engaging the outstanding flanges 19 of the door arms to maintain the doors fully closed, and said hooks are also furnished with auxiliary or preliminary supporting ledges 28 with which the said flanges of the door arms cooperate to support the doors in partially closed position. The doors are usually closed by first swinging them upwardly until the auxiliary ledges 28 of the hooks may be brought into supporting engagement with the door arms 18, this preliminary portion of the closing movement being easy of accomplishment. As the final 115 closing movements of the doors can only be 120 125 130

effected by the application of considerable force, means are preferably provided for enabling a removable lever to be employed for prying the doors from partly closed to fully closed position. In a car construction involving certain features of my invention, it may be advantageous to provide fulcrum means for the removable door prying lever of the character disclosed in Patent No. 10 1,440,280 granted December 26, 1922, to W. F. Cremeen, each of the door arms 18 being formed at its outer end with an aperture 29 through which a removable lever or prying bar (not shown) may be inserted for 15 forcing one or the other of the doors to closed position. The lever receiving apertures 29 are preferably disposed in substantial alinement longitudinally of the car.

In car construction of the present type it 20 not infrequently happens that the use of a prying lever in conjunction with lever receiving apertures 29 in the manner contemplated in the Cremeen patent, above referred to, is rendered impossible because certain parts of the car interfere with the necessary movement of the lever. In the 25 present embodiment of my invention, for example, the insertion of the door prying lever through the holes 29 would result in causing the lever to contact with the flange 6 at the lower edge of the side plate extension 4. Such an occurrence might well cause 30 personal injury to the trainman. In order to overcome any such difficulty of operation 35 of the removable prying bar, each door arm 18, in addition to being provided with the holes 29, is provided with a lever receiving hole 30, the holes 29 and 30 of each arm being in spaced relation and the holes 30 40 preferably being in alinement with each other. With such a construction the removable door prying lever may be entered through the hole 29 of one arm and extend into the hole 30 of the adjacent arm, thus 45 causing the lever to stand in an oblique position such that its outer end will extend outwardly away from the car and come within convenient reach of the workman.

The preferred form of car construction 50 herein disclosed, involving the offsetting of the side plate extension 4 from the general plane of the car side 1, as well as notching of the side plate extensions at points adjacent the door supporting hooks 20, permits 55 the hooks to be applied closely against the outer faces of the respective plates 4 and also enables a car of this general type to be constructed without exceeding the available clearance limits.

60 What I claim is:—

1. A railway car having a side with portions of its lower edge extending in a substantially horizontal plane, a hinged door forming a closure for the discharge opening in the floor of said car, the plane of the

door being above the plane of the horizontal portions of the lower edge of the car side and said car side being formed near the free end of the door with a notch extending adjacent to the plane of said door, a door arm 70 affixed to the door and extending outwardly beyond the plane of the car side at the notched portion of the latter, and a door supporting member pivotally mounted upon the car side and adapted to co-operate with 75 said arm for supporting said door.

2. A railway car having a floor, a side extending below said floor and provided at its lower edge with a marginal flange, a door in the floor of the car, the plane of the door 80 being angularly disposed with respect to the plane of the said marginal flange, a door supporting member pivoted upon the car side, and an arm carried by said door and extending outwardly from the edge thereof 85 and adapted to be supportingly engaged by said supporting member, said marginal flange being interrupted adjacent said supporting member.

3. A railway car having a side and a 90 floor, the said side extending slightly below the lines of the floor and being provided with a marginal flange along its lower edge, a door in said floor, a door supporting member pivoted upon the car side and adapted 95 to support said door, said marginal flange being interrupted to clear said supporting member, an arm carried by the door and extending outwardly from the edge thereof, said arm being adapted to cooperate with 100 said supporting member to support said door in closed position, and a reinforcing member attached to the inner face of the car side to reinforce the latter at the point where the said marginal flange is interrupted. 105

4. A railway car having a side and a floor, the said side extending slightly below the lines of the floor and being provided with a marginal flange bordering its lower 110 edge, a door in the floor of the car, a door supporting member pivoted upon the car side, said car side being notched adjacent said door supporting member and said marginal flange being interrupted so as to clear 115 said pivoted supporting member, an arm carried by the door and extending outwardly from the edge thereof and adapted to co-operate with said pivoted supporting member to support said door, said arm extending beneath the notched portion of the car side and projecting outwardly beyond said side, and a reinforcing member attached to the inner face of the said side to reinforce the latter at the notched portion thereof. 120 125

5. A railway car having a side, a floor having a discharge opening therein, a pair of inclined doors hinged to the car body and adapted to close said discharge opening, door arms respectively secured to said doors 130

and extending outwardly beyond the car side, and means movably mounted upon the car side for cooperating with the respective arms to maintain said doors in closed position, the lower edge of said side adjacent the free edges of said doors being inclined to correspond substantially to the inclination of said doors, and the said side being provided at its lower edge with stiffening means, portions of which extend in opposite directions with respect to the plane of the said side of the car.

6. A railway car having a side, a floor, a hinged door swinging on an axis extending 15 transversely of the car, the plane of said door being slightly above the bottom edge of the said car side and said side being formed with a notch extending toward said door, a door supporting member movably 20 mounted upon the car side, and a door arm affixed to the door, the said arm extending beyond the plane of the car side at the notched portion thereof and being adapted to cooperate with said door supporting member 25 to support said door.

7. A railway car involving a door hinged to the car body, an arm carried by said door, and means for cooperating with said arm to support said door, said arm being provided 30 with a plurality of means for alternatively receiving and cooperating with a removable door prying lever.

8. A railway car involving a door hinged to the car body, an arm carried by said door 35 and extending outwardly therefrom, and means for cooperating with said arm to support said door, said arm being provided with a plurality of apertures adapted alternately to receive a removable door prying lever.

9. A railway car involving a door hinged to the car body, and an arm carried thereby, said arm being provided adjacent one of the edges of said door with a plurality of means 45 adapted alternately to receive and cooperate with a removable door prying lever.

10. A railway car involving a door hinged to the car body, and an arm carried by said door and extending outwardly therefrom, 50 said arm being provided adjacent one of the edges of said door with a plurality of apertures adapted alternately to receive a removable door prying lever.

11. A railway car involving a door hinged 55 to the car body, and an arm carried by and extending outwardly from said door, said arm being provided with a plurality of apertures adapted alternately to receive a removable door prying lever, said apertures 60 being spaced in the direction of the hinge axis of said door.

12. A railway car involving a pair of doors hinged to the car body and having their free edges adjacent each other when 65 said doors are closed, and arms respectively

carried by said doors and extending outwardly therefrom near the free edges thereof, each of said arms being provided with a plurality of apertures adapted to receive a removable door prying lever.

13. A railway car involving a pair of doors hinged to the car body and having their free edges adjacent each other when the doors are in closed position, and arms respectively carried by said doors and extending outwardly 70 therefrom near the free edges thereof, each of said arms being provided with a plurality of apertures adapted to receive a removable door prying lever, the respective apertures in each arm being at different distances from the center line of the car.

14. A railway car involving a pair of doors hinged to the car body and having their free edges adjacent each other when the doors are closed, and arms extending 85 outwardly from said doors near their free edges, each of said arms being provided with an aperture and with an opening forming a lever seat spaced inwardly from said aperture, and the said aperture of either arm and 90 the said lever seat of an adjacent arm being adapted simultaneously to cooperate with a removable door prying lever.

15. A railway car involving a pair of doors hinged to the car body, the free edges 95 of said doors being adapted to stand adjacent each other when the doors are closed, and arms respectively carried by said doors and extending outwardly therefrom near the free edges thereof, each of said arms being provided with an aperture adapted to receive a removable door prying lever, said apertures being in spaced relation such that one of them is closer to the center line of the car than is the other.

16. A railway car involving a side sheet, a floor having a discharge opening therein, and a pair of hinged doors for closing said opening having their free edges adjacent each other, an arm carried by each door and extending outwardly beyond the side sheet to cooperate with door supporting members, the doors being above the plane of the lower edge of the side sheet, and the side sheet being notched adjacent the free edges of the doors to receive the said door arms.

17. A railway car involving a side sheet, a floor having a discharge opening therein, and a pair of doors hinged at their remote edges and having their free edges adjacent 120 each other to close said opening, the doors being above the bottom edge of the side sheet, the side sheet being notched adjacent the said free edges of the doors, and means for supporting the doors in closed position.

18. A railway car involving a side sheet, a hopper, and a pair of doors for the hopper having their free edges adjacent each other when the doors are in closed position, the bottom edge of the side sheet being disposed 130

in a plane below the free edges of the doors, and being notched adjacent the free edges of the doors.

19. A railway car involving a side sheet, a hopper, and a hinged door for the hopper, the bottom edge of the side sheet being disposed in a plane below the lower edge of the door, an arm carried by the door and extending outwardly beyond the side sheet, and means movable into engagement with the said arm for supporting the door in closed position, the said bottom edge of the side sheet being notched to receive the door arm so as to permit the said means to engage the door arm at a point above the general plane of the bottom edge of the side sheet.

20. A railway car having a side and a floor, a hinged door in the floor of the car for controlling the discharge of lading therefrom, and means for supporting the door in closed position involving a movable member and a fixed member, one of said members being carried by the door and the other by the car, the lower edge of the car side being disposed below the door opening and being notched so as to permit the said movable member to move into door supporting engagement with the fixed member at a point above the general level of the lower edge of the side sheet. 30

In testimony whereof I affix my signature.

WILLIAM E. WINE.
